UNITED STATES PATENT OFFICE

105,447

DESIGN FOR A DISPLAY COUNTER UNIT

James F. Urbanek, Elmwood Park, Ill.

Application June 11, 1937, Serial No. 69,794

Term of patent 14 years

To all whom it may concern:

Be it known that I, James F. Urbanek, a citizen of the United States, residing at Elmwood Park, in the county of Cook and State of Illinois, have invented a new, original, and ornamental Design for a Display Counter Unit, of which the following is a specification, reference being had to the accompanying drawing forming a part thereof.

The figure is a front perspective view of a display counter unit showing my new design.

I claim:

The ornamental design for a display counter unit substantially as shown.

JAMES F. URBANEK,
